CLAIM

The ornamental design for a footbed, as shown and described.

DESCRIPTION

FIG. 1 is a bottom, front, left-side perspective view of a footbed according to our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a bottom plan view thereof;

FIG. 7 is a top plan view thereof;

FIG. 8 is a bottom, front, left-side perspective view of a second embodiment thereof;

FIG. 9 is a front elevation view of FIG. 8;

FIG. 10 is a rear elevation view of FIG. 8;

FIG. 11 is a left-side elevation view of FIG. 8;

FIG. 12 is a right-side elevation view of FIG. 8;

FIG. 13 is a bottom plan view of FIG. 8; and,

FIG. 14 is a top plan view of FIG. 8.

The dot-dash broken lines represent boundaries of the claimed design and form no part of the claimed design. All other broken lines represent portions of the footbed that form no part of the claimed design.
